UNITED STATES PATENT OFFICE

JESSE G. KING, OF DAYTON, OHIO, ASSIGNOR, BY MESNE ASSIGNMENTS, TO FRIGID-AIRE CORPORATION, A CORPORATION OF DELAWARE

REFRIGERATING APPARATUS

Application filed October 23, 1923, Serial No. 670,358. Renewed December 3, 1927.

This invention relates to automatic controlling mechanisms, and more particularly to means for automatically initiating and discontinuing the alternate periods of expanding and condensing a vaporous refrigerant of a refrigerating machine.

In an application of Jesse G. King and Sylvester M. Schweller, Serial No. 670,357 for Refrigerating apparatus, filed October 23, 1923, there is disclosed a controlling device adapted to stop and start the cycles of a refrigerating machine in response to changes of pressure corresponding substantially to changes of temperature above and below a certain range in a part of the refrigerating apparatus, said controlling device including a member which may be so adjusted as to increase the range of pressure within which the device operates without changing one of the limits. Said member may be set, for example, so that the higher pressure point at which the controlling device will operate may be raised while the lower pressure point at which it will operate remains the same. It is among the objects of this invention to render the said member effective or ineffective at will.

The invention consists in a manually controllable means for achieving the objects, which is exemplified in the drawings, described in the ensuing specification and defined in the appended claims.

In the accompanying drawings in which like parts are indicated by like reference characters throughout the several views,

Fig. 1 is a front elevation of a refrigerating cabinet with parts broken away to disclose a part of the interior thereof and mechanism inclosed therein;

Fig. 2 is an elevation of a fragment of the controlling device showing the application of this invention; and

Fig. 3 is a section on the line 3-3 of Fig. 2 and also through the front cover plate of the machine compartment of the cabinet.

An exemplary and preferred embodiment of the invention is illustrated and described in operative relation to a standard refrigerating apparatus, of the compressor-con-

denser-expander circuit type, incased in a household refrigerating cabinet.

In Fig. 1, A indicates the usual cabinet having in its lower portion a "machine" compartment B, housing a machine unit C comprising a compressor and its prime mover, a condenser, and a means for controlling the starting and duration of the alternate periods of condensing and expanding the refrigerant according to requirements in ordinary use. B' is a removable front cover plate for compartment B. D is the cooling or refrigerating compartment which contains the expanding unit or "boiler" E, and F is the storage compartment for food or other materials to be cooled, there being air circulating openings G and H between compartments D and F. Suitable doors close the compartments D and F and afford access to them from the front of the cabinet.

The construction and relative arrangement of the compressor, condenser and prime mover, constituting the essential elements of the machine unit C, may be such as is disclosed in the U. S. patent to Bechtold and Mellowes, No. 1,276,619, patented August 20, 1918.

The cycles of the apparatus disclosed correspond to the periods of operation and non-operation of the condenser, and, as the operation of the condenser is effected by the prime mover, stopping and starting of the prime mover 10, here indicated as an electric motor, stops and starts the periods of condensation and expansion.

The expanding unit E may be suspended or otherwise mounted in the compartment D, as by hangers or brackets 11. It comprises the usual evaporating or expansion tank 12 and evaporating tubes or coils which are not visible in Fig. 1, because immersed in a brine tank 13. Numeral 14 indicates the liquid or high pressure conductor leading from the high pressure side of the compressor to the lower portion of the evaporating tank 12, and 15 indicates the low pressure or vapor conductor leading from the upper portion of the evaporating tank to the lower pressure side of the compressor. According to usual

practice a liquid control valve, (not shown) of any approved type, may regulate the discharge of refrigerant from the conductor 14 into evap orating tank 12.

5 A thermostatic tube 16 has one end communicating with a bulb within the brine tank and its other end communicating with a pressure-responsive device such as a diaphragm or corrugated tubular bellows 28 which constitutes a part of the controlling means hitherto mentioned. As there is a direct connection between the temperature and pressure of gases the pressure in tube 16 will vary in accordance with the temperature of the brine in the brine tank. In the embodiment illustrated the motor 10 is started by a relatively high pressure in the thermostatic tube 16 (corresponding to the upper limit of temperature at the expanding unit 15 E) at which the control mechanism is set to operate so as to close a switch in the motor circuit; and the motor is stopped by a relatively low pressure in said tube 16 (corresponding to the lower limit of temperature 20 at the expanding unit) at which the control mechanism is set to operate so as to open the switch in the motor circuit.

The switching device is herein shown, for illustrative purposes, as an electric switch 30 for opening and closing the motor circuit may be a snap switch (not shown) of any suitable type disposed in a switch box 17 and adapted to be opened and closed by means presently to be described that responds to different pressures in the thermostatic tube 16.

The switch box 17 and a platform like extension 18 thereon constitute a base for supporting the controlling means, by which 40 the rod 19 that is connected to the switch may be moved to open and close the switch. From the extension 18 rises a plurality of rigid standards 20, the upper ends of which are reduced and support a rigid frame 21, 45 which comprises an arm or projection 22 extending over the switch box 17, and a part 23 that overhangs the platform-like extension 18. Threaded studs 24 are formed on the reduced upper ends of standards 20. 50 These studs pass through holes in the frame 21; nuts 25, engaging said studs, secure the frame rigidly on the standards. A bearing member 26 depends from each edge of frame 21 between two of the supporting standards 55 20, each bearing member having a V-shaped notch 27 at its lower end. Although Figs. 1 and 2, being side elevations, show only one of these bearing members 26 it will be understood that as one depends from each 60 side of the frame 21, an elevation from the other side would present the same appearance.

There are preferably four of the standards 20. In the space between standards 65 20 is a flexible diaphragm consisting of a

tubular metallic bellows 28, the lower end of which is sealed, fluid tight, to-said platform-like extension 18 in any suitable manner, but is provided with an opening communicating with the thermostatic tube 16. 70 The upper end of the bellows 28 is sealed to a head 29 from which an arm 30 extends beneath the arm 22 of the frame 21 and which is connected to the arm 22 by a link 31. Rising from the head 29 there is a central bearing standard 32 having a V-shaped notch 33 in its upper end, the center or apex line of said notch being parallel with, but displaced laterally from the center or apex lines of notches 27 in depending bearings 26. A 75 lever 34, constituting an operating member, is fulcrumed between its ends in the notches 27 by means of knife bearings 35. A knife bearing 36 carried on said lever rests in the notch 33 of the upright bearing 32 which rises from the bellows head 29. At its right end,—as viewed in Fig. 2,—lever 34 is pivoted at 37 to the switch operating rod 19 before mentioned. On the other end of lever 34 there is an adjustable weight 38 which may be fixed at various points along the arm of the lever by means of a set screw 39. The weighted arm of lever 34 is preferably guided by a guide member 40, here shown as an L-shaped bracket depending from the under side of the extension 23 of frame 21. Said guide member 40 has an elongated slot 41 which serves not only to prevent lateral movements of the lever arm, but also to limit the range of oscillation of the lever 34 90 so that no undue strain may be transmitted to the snap switch after it has been opened or closed. The structure of the switch operating lever, its mount and connection to the bellows is fully disclosed in an application 95 of Bechtold and Mellowes, filed February 5, 1917, Serial No. 146,715.

As thus far described, it will be apparent that if sufficient pressure is admitted to the bellows 28 the latter will expand and cause 100 the lever 34 to move about the fulcrum on bearings 26, turning the lever so as to raise the weight 38 and to depress the opposite end of said lever thus forcing the rod 19 downward. This closes the switch. Decrease of pressure in the bellows 28 will permit the weight 38 to depress the arm of the lever on which the weight is carried and raise the opposite end, thus lifting the rod 19 105 and finally opening the switch. It will be understood that the switch does not make or break contact in the motor circuit until at or near the limits of movement of lever 34 and rod 19, in the manner characteristic of snap switches. 110

Associated with the mechanism thus far described is a means for varying the temperature range of the evaporating period by varying the upper limit thereof without varying the lower limit. This means is de- 115 120 125

scribed and claimed in the aforesaid application of Jesse G. King and Sylvester M. Schweller and comprises the elements to be now described.

5 Pivoted by pin 42 on the upper side of overhanging extension 23 of frame 21 is an arm 43 upon which there is mounted a weight 44 adapted to be slid longitudinally of arm 43 and to be secured in any desired 10 adjusted position by set screw 45. The pivot pin 42 about which arm 43 may swing is mounted between bearings 46 struck up from a bracket 47 secured on the upper side of frame 21 by a screw 48 which may also 15 serve to secure guide member 40 to the under side of said frame. Bracket 47 projects over the end of extension 23 and has two bearing ears 49 for a purpose to be presently stated. Arm 43 extends above the weighted 20 arm of lever 34 and trends in the same general direction. The amplitude of movement of the lever 34 is such that before it reaches the upper limit of its oscillation and before it has closed the switch, the weight 38 will 25 contact with the weight 44 when the latter is in its operative position, and said weight 44 will then add its resistance to that of the weight 38 and delay movement of the lever 34 until additional pressure is built up in 30 bellows 28 so that the switch will be opened only under a higher pressure than it would be otherwise.

By adjusting the weight 38 toward the end of lever 34, it will be apparent that the 35 switch will open when the pressure in bellows 28 is at a certain predetermined low pressure and the expansion unit at a corresponding temperature and that by moving weight 38 nearer to the fulcrum the switch 40 will open only when the pressure in the bellows is still lower, corresponding to a lower temperature at the expansion unit; likewise that the difference between opening and closing temperatures and pressures may be varied by adjusting the weight 38. It will also 45 be apparent that with the adjustable weight 38 alone controlling the range of pressure and temperature between opening and closing of the switch, the pressure that closes 50 the switch cannot be varied without also varying the pressure that opens it. By adding to the weight 38 toward the end of its upward movement the resistance of weight 55 44, it will be perceived that the switch may be set to close at any desired pressure within operative limits without changing the setting for opening the switch which will, in this event, open always at the same pressure. 60 The weight 44 adds a non-elastic resistance to the movement of lever 34. This resistance of course remains substantially constant on lever 34 after it has moved a predetermined distance and picked up said weight 65 44.

Assuming the upward movement of weighted arm of lever 34 to be resisted by weight 38 alone, and that the weight be so adjusted on the lever that the switch will be closed under, say, a pressure in bellows 28 corresponding to a temperature of 28° F. at the expansion unit, and opened under a pressure corresponding to, say, 10° F., it will be apparent that if, for any reason, it were desired to adjust the weight away from the fulcrum, so as to close the switch at a higher pressure and temperature, this adjustment would cause the switch to open under a higher temperature and pressure than it did under the previous adjustment. But by introducing the additional weight 44 in the upward path of movement of the weighted arm of lever 34 such additional resistance to the movement of the latter will be added that a still higher temperature and pressure must be attained, before the switch will be opened, without changing the temperature and pressure at which it will be closed.

In accordance with this invention the additional resistance may be rendered operative or inoperative instantly at will. The apparatus may be set to operate so as to maintain a given range of temperature say between 10° and 28° F. under the control of the bellows 28 coacting with the lever 34 and weight 38 only. Should the expanding unit accumulate frost or ice to an undesirable extent, the additional resistance of the weight 44, properly adjusted, may be introduced into the path of upward movement of the weighted arm of lever 34, thereby raising the limit of temperature and pressure at which the switch will be closed so that the evaporating or expanding cycle will be prolonged and the temperature at the expanding unit will rise above 32° F. and cause the ice and frost to melt from the expanding unit thus avoiding the necessity of stopping the refrigerating mechanism for a prolonged period to defrost the expanding unit.

The additional weight, 44, according to this invention, may be disabled or rendered ineffective by a cam, tappet, or the like, such as 50, carried by a rock shaft 51 which passes through holes in the bearing ears 49 on the end of bracket 47 before described. The cam or tappet 50 lies between said bearing ears and the arm 43 rests upon it. Said shaft 51 projects through the cover plate B' of the machine compartment and carries a finger lever 52 by means of which the shaft may be rocked from the exterior of the cabinet. The construction and relationship of parts is such that when the cam or tappet is rocked into position to elevate the weight 44 beyond the extreme upper position of weight 38, said weight 44 will remain in this position until the shaft 51 is rocked back again whereupon the weight 44 will resume

its operative relation to the arm 34 and weight 38.

While I have illustrated and described a preferred embodiment of the invention it is not my intention that the invention shall be limited except by the appended claims.

What I claim and desire to secure by Letters Patent of the United States is:

1. In apparatus of the class described, a movable operating member, a frame on which it is mounted, an arm carrying a weight pivoted on said frame and arranged to be interposed in the path of movement of said operating member, and a manually controllable device adapted to be interposed between the frame and arm, and to be moved in such manner as to lift said arm at will out of the path of movement of said operating member.
2. In apparatus of the class described, a movable operating member, a pivoted weighted arm arranged to be interposed in the path of said operating member, a shaft and a lifting device connected thereto in position to engage said weighted arm, and a manually movable device for rocking said shaft and thereby causing said lifting device to lift said arm from the path of said operating member.
3. In apparatus of the class described, a movable operating member, a pivoted weighted arm arranged to be interposed in the path of said operating member, a shaft carrying a cam disposed beneath said weighted arm, and a handle on said shaft for rocking the cam and lifting said weighted arm out of the path of said operating member.
4. In an apparatus of the class described, a movable operating member, means interposed in the path of said member, said means including a pivoted arm and a weight adjustably carried thereby and manually movable mechanism for moving said means from the path of said operating member.
5. In an apparatus of the class described, a movable operating member, means interposed in the path of said member, said means including a pivoted arm and a weight adjustably carried thereby, and a shaft and a lifting device connected thereto in position to engage said means, and a manually movable device for rocking said shaft and thereby causing said lifting device to move said arm from the path of said operating member.
6. In an apparatus of the class described, a switching device, a movable operating member for controlling the device, adjustable means for normally regulating the operation of said member, and means for temporarily modifying the operation of said member, said means including a pivoted weight arranged to yieldingly resist movement of said operating member, said weight

being movable at will into and out of effective operative relation with the operating member without disturbing the adjustment of said adjustable means.

7. In an apparatus of the class described, a switching device, a movable operating member for controlling the device, means set for normally regulating the operation of said member, and means for temporarily modifying the operation of said member, said means including a pivoted weight arranged to yieldingly resist movement of said operating member, said weight being movable at will into and out of effective operative relation with the operating member without disturbing the setting of the first means.

8. In combination, a cabinet; a switching device within the cabinet, a movable operating member for controlling the device, means set for normally regulating the operation of said member, means for temporarily modifying the operation of said member, said means including a weight arranged to yieldingly resist movement of said operating member, said weight being movable at will into and out of effective operative relation with the operating member without disturbing the setting of the first means, and means extending to the exterior of the cabinet for moving said weight.

In testimony whereof I hereto affix my signature.

JESSE G. KING.
